DEPOSITION FORM

Carl L. Beal, Cuyahoga Falls, Ohio, assignor to
American Anode Inc., Akron, Ohio, a corpora-
tion of Delaware

Application April 6, 1940, Serial No. 328,329

14 Claims. (Cl. 18—41)

This invention relates to an improved deposition form for use in making rubber nasal masks of the type used, for example, by aviators for high altitude flying.

This invention comprises a deposition form with certain novel structural features incorporated therein so that an improved nasal mask may be made efficiently, cheaply, and with a minimum of time. The mask produced is of one-piece integral construction.

Generally, the improved form which is the subject of this invention comprises a bulbous portion, two rod-like arms extending from spaced apart points on the bulbous portion and merging to form a ring-like structure, and a stem portion on the ring-like structure opposite to and projecting in a direction generally away from the bulbous portion. The form is coated with rubber by any of the usual methods such as by depositing rubber from an aqueous dispersion of rubber by the use of a coagulant solution such as any of those disclosed in U. S. Patent No. 1,996,090, granted to Edward A. Willson.

This invention can best be understood by reference to the accompanying drawings showing both the construction of the form and the principal steps in a preferred method of making a rubber nasal mask, as well as the rubber article so produced.

Fig. 1 is an elevation of the deposition form of this invention mounted on a support and immersed in a body of latex.

Fig. 2 is an elevation of the rubber coated form with a portion of the rubber broken away for clarity of illustration.

Fig. 3 is an elevation illustrating removal of the form from the rubber deposit.

Fig. 4 is an elevation in profile of the nasal mask.

Fig. 5 is an elevation showing the rear view of the nasal mask.

Fig. 6 is a cross-sectional elevation of the mask taken along line 6—6 of Fig. 5.

Fig. 7 is a cross-sectional elevation of the deposition form taken along line 7—7 of Fig. 1.

A deposition form 10 embodying the present invention comprises a bulbous portion 11, and two rod-like arms 12, 12 of generally semi-circular cross section projecting from spaced apart points on the bulbous portion 11. These arms merge to form a ring-like structure 13 lying in a concave plane. A stem portion 14 is provided on this ring-like structure 13 located opposite to and projecting generally away from the bulbous portion 11. A fin-like portion 15 is located

on the bulbous portion 11 and projects outwardly in a direction opposite the stem portion 14. The bulbous portion 11 and the fin-like portion 15 are provided with a backing portion 16 which serves to produce a flat back and is arranged so as to leave open spaces between the backing portion 16 and each of the rod-like arms 12, 12 for a substantial distance along the rod-like arms as indicated at 25, 25. These two open spaces are joined by a groove 17 in the bulbous portion 11 between the rod-like arms 12, 12 with the groove having an angular shoulder formed by the backing portion 16. The deposition form 10 consists of two elements separably joined, as with dowel pins, at two points 18, 19 on the ring-like structure 13 to give a unitary structure. These points lie in linear relationship with one of the points 18, located near the stem portion 14 of the form and with the other point 19 located near the bulbous portion 11 of the form.

The deposition form is mounted on a support 20 extending from the backing portion 16 for the dipping operation and is preferably mounted with the stem portion 14 up so as to lessen any danger of the form coming apart at the two joints 18, 19. The deposition form is coated with rubber, as by immersion in latex (Fig. 1) and the rubber is dried and vulcanized. The rubber is cut around the edge 21 of the backing portion 16 and this section of the rubber is removed. The form is then separated at the two points 18, 19 and the bulbous portion 11 with its attached portion of the ring-like structure 13 is removed through the hole produced by the cutting operation. The stem portion 14 with the remainder of the ring-like structure is then removed through this same hole. The nasal mask (Fig. 4) is finished by trimming the edge of the bulbous portion of the rubber deposit to the edge of the projecting portion 22 (Fig. 6) that is formed by the groove 17. The end of the stem portion is cut off and the portion of the mask that fits the face around the nose 23 is smoothed to a feather edge as by buffing with a buffering wheel 24.

The deposition form of this invention may be constructed of any usual material that is non-corrodible. These materials include porcelain, stone, aluminum, various metal alloys, and the like, with the preferred material being aluminum.

Although this invention has been described with particular reference to a preferred form and to the resulting nasal mask produced therewith it is understood that the invention is not

limited to this preferred embodiment but shall be unlimited within the spirit and scope of the appended claims.

I claim:

1. A deposition form for use in manufacturing rubber nasal masks, said deposition form comprising a bulbous portion, two rod-like arms extending from spaced apart points on the bulbous portion and merging to form a ring-like structure, a stem portion on the ring-like structure opposite to and projecting generally away from the bulbous portion, said deposition form comprising two elements separably joined at two points on the ring-like structure to form a unitary structure, one point being on one of the rod-like arms and the other point being on the other of the rod-like arms.

2. A deposition form for use in manufacturing rubber nasal masks, said deposition form comprising a bulbous portion, two rod-like arms extending from spaced apart points on the bulbous portion merging to form a ring-like structure lying in a concave plane, a stem portion on the ring-like structure opposite to and projecting generally away from the bulbous portion, said deposition form comprising two elements separably joined at two points on the ring-like structure, one point being on one of the rod-like arms and near the stem portion and the other point being on the other of the rod-like arms and near the bulbous portion.

3. A deposition form for use in manufacturing rubber nasal masks, said deposition form comprising a bulbous portion, two rod-like arms of generally semi-circular cross section extending from spaced apart points on the bulbous portion and merging to form a ring-like structure lying in a concave plane, a stem portion on the ring-like structure opposite to and projecting generally away from the bulbous portion, a backing portion on the back of the bulbous portion so constructed and arranged as to provide open spaces between the backing portion and the two rod-like arms for an appreciable distance along the two arms, said deposition form comprising two elements separably joined at two points disposed in linear relationship on the ring-like structure, one point being on one of the rod-like arms near the stem portion and the other point being on the other of the rod-like arms near the bulbous portion.

4. A deposition form for use in manufacturing rubber nasal masks, said deposition form comprising a bulbous portion, two rod-like arms of generally semi-circular cross section extending from spaced apart points on the bulbous portion and merging to form a ring-like structure lying in a concave plane, a stem portion on the ring-like structure opposite to and projecting generally away from the bulbous portion, a fin-like portion on the bulbous portion projecting generally away from the stem portion, a backing portion on the rear of the bulbous portion so arranged as to provide open spaces between the backing portion and the two rod-like arms for an appreciable distance along the two arms, a hollowed out section between the rod-like arms on the bulbous portion forming a groove between the bulbous portion and the backing of the bulbous portion with the backing portion providing a vertical side of the groove, and the groove being arranged as a continuation of the open spaces between the backing portion and the two rod-like arms, said deposition form comprising two elements separably joined to form a unitary structure at two points

5 10 15 20 25 30 35 40 45 50 55 60 65 70 75 80 85 90 95 100 disposed in linear relationship on the ring-like structure, one point being on one of the rod-like arms and near the stem portion and the other point being on the other of the rod-like arms and near the bulbous portion.

5. A deposition form for use in manufacturing rubber nasal masks, said deposition form comprising a bulbous portion, two rod-like arms of generally semi-circular cross section projecting from spaced apart points on the bulbous portion and merging to form a ring-like structure lying in a concave plane, a stem portion on the ring-like structure opposite to and projecting generally away from the bulbous portion, a fin-like portion on the bulbous portion projecting generally away from the stem portion, a backing portion on the back of the bulbous portion so arranged as to provide open spaces between the backing portion and the two rod-like arms for an appreciable distance along the two arms, a hollowed out section between the rod-like arms on the bulbous portion forming a groove between the bulbous portion and the backing of the bulbous portion with the backing portion providing a vertical side of the groove, the groove being arranged as a continuation of the open spaces between the backing portion and the two rod-like arms, said deposition form comprising two elements separably joined to form a unitary structure at two points disposed in linear relationship on the ring-like structure, one point being on one of the rod-like arms near the stem portion and the other point being on the other of the rod-like arms near the bulbous portion, and said deposition form being mounted, preparatory for dipping, on a support attached to the backing portion of the form with the fin-like portion projecting generally downwardly and the stem portion projecting generally upwardly.

6. A deposition form for use in manufacturing rubber nasal masks, said deposition form comprising a bulbous portion, two rod-like arms of generally semi-circular cross section extending from spaced apart points on the bulbous portion and merging to form a ring-like structure, a stem portion on the ring-like structure, said deposition form comprising two elements separably joined at two points on the ring-like structure to form a unitary structure, one point being on one of the rod-like arms and the other point being on the other of the rod-like arms.

7. A deposition form for use in manufacturing rubber nasal masks, said deposition form comprising a bulbous portion, two rod-like arms extending from spaced apart points on the bulbous portion and merging to form a ring-like structure, a projecting stem portion on the ring-like structure, said deposition form comprising two elements separably joined at two points on the ring-like structure to form a unitary structure, the projecting stem portion being disposed on the ring-like structure at a position between the said two points of joinder.

8. A deposition form for use in manufacturing rubber nasal masks, said deposition form comprising a bulbous portion, two rod-like arms extending from spaced apart points on the bulbous portion and merging to form a ring-like structure lying in a concave plane, a stem portion on the ring-like structure opposite to and projecting generally away from the bulbous portion, said deposition form comprising two elements separably joined at two points on the ring-like structure to form a unitary structure, one point being on one of the rod-like arms and the other point being on the other of the rod-like arms.

9. A deposition form for use in manufacturing rubber nasal masks, said deposition form comprising a bulbous portion, two rod-like arms extending from spaced apart points on the bulbous portion and merging to form a ring-like structure, a stem portion on the ring-like structure opposite to and projecting generally away from the bulbous portion, said deposition form comprising two elements separably joined at two points on the ring-like structure, one point being on one of the rod-like arms and near the stem portion and the other point being on the other of the rod-like arms and near the bulbous portion.

10. A deposition form for use in manufacturing rubber nasal masks, said deposition form comprising a bulbous portion, two rod-like arms extending from spaced apart points on the bulbous portion and merging to form a ring-like structure, a stem portion on the ring-like structure opposite to and projecting generally away from the bulbous portion, said deposition form comprising two elements separably joined at two points disposed in linear relationship on the ring-like structure, one point being on one of the rod-like arms near the stem portion and the other point being on the other of the rod-like arms near the bulbous portion.

11. A deposition form for use in manufacturing rubber nasal masks, said deposition form comprising a bulbous portion, two rod-like arms extending from spaced apart points on the bulbous portion and merging to form a ring-like structure, a stem portion on the ring-like structure opposite to and projecting generally away from the bulbous portion, a backing portion on the back of the bulbous portion so constructed and arranged as to provide open spaces between the backing portion and the two rod-like arms for an appreciable distance along the two arms, said deposition form comprising two elements separably joined at two points on the ring-like structure to form a unitary structure, one point being on one of the rod-like arms and the other point being on the other of the rod-like arms.

12. A deposition form for use in manufacturing rubber nasal masks, said deposition form comprising a bulbous portion, two rod-like arms extending from spaced apart points on the bulbous portion and merging to form a ring-like structure, a stem portion on the ring-like structure

opposite to and projecting generally away from the bulbous portion, a fin-like portion on the bulbous portion projecting generally away from the stem portion, said deposition form comprising two elements separably joined at two points on the ring-like structure to form a unitary structure, one point being on one of the rod-like arms and the other point being on the other of the rod-like arms.

10 13. A deposition form for use in manufacturing rubber nasal masks, said deposition form comprising a bulbous portion, two rod-like arms extending from spaced apart points on the bulbous portion and merging to form a ring-like structure, a stem portion on the ring-like structure opposite to and projecting generally away from the bulbous portion, a hollowed out section between the two rod-like arms on the bulbous portion forming a groove between the bulbous portion and the backing of the bulbous portion with the backing portion providing a vertical side of the groove, said deposition form comprising two elements separably joined at two points on the ring-like structure to form a unitary structure, one point being on one of the rod-like arms and the other point being on the other of the rod-like arms.

14. A deposition form for use in manufacturing rubber nasal masks, said deposition form comprising a bulbous portion, two rod-like arms extending from spaced apart points on the bulbous portion and merging to form a ring-like structure, a stem portion projecting outwardly from the ring-like structure, a backing portion on the back of the bulbous portion so constructed and arranged as to provide open spaces between the backing portion and the two rod-like arms for an appreciable distance along the two arms, a hollowed out section between the rod-like arms on the bulbous portion forming a groove between the bulbous portion and the backing of the bulbous portion with the backing portion providing a vertical side of the groove and the groove being arranged as a continuation of the open space between the backing portion and the two rod-like arms, said deposition form comprising two elements separably joined at two points on the ring-like structure to form a unitary structure, one point being on one of the rod-like arms and the other point being on the other of the rod-like arms.

CARL L. BEAL.
